UNITED STATES PATENT OFFICE.

JOHN D. FINNEGAN, OF NEWCOMB, NEW YORK.

CRATE.

1,295,723.

Specification of Letters Patent.

Patented Feb. 25, 1919.

Application filed November 21, 1918. Serial No. 263,558.

To all whom it may concern:

Be it known that I, JOHN D. FINNEGAN, a citizen of the United States, residing at Newcomb, in the county of Essex and State 5 of New York, have invented new and useful Improvements in Crates, of which the following is a specification.

This invention relates to crates of the folding or collapsible type, the broad object 10 in view being to provide a simple, cheap and durable crate which is capable of being folded compactly for reshipment, storage or transportation, and which, when folded, is particularly adapted to resist and withstand 15 crushing strains, and in the case where a large number of crates are packed, or stored or shipped in piles.

With the above and other objects in view, the invention consists in the construction, 20 combination and arrangement of parts, as herein described, illustrated and claimed.

In the accompanying drawings:

Figure 1 is a perspective view of the main body of the crate omitting the top and bottom thereof.

Fig. 2 is a vertical cross section through the crate, showing the top and bottom supporting means.

Fig. 3 is a horizontal section through the 30 crate when folded.

Fig. 4 is a fragmentary perspective view through one corner of the body of the crate partly broken away in section.

Fig. 5 is a fragmentary perspective view 35 of the central portion of one end of the crate, showing the form of joint between the twin sections of the end members of the crate.

Fig. 6 is a detail perspective view of the 40 scarfed inner end of one of the end members of the crate.

Fig. 7 is a fragmentary perspective view showing the means for fastening the top or cover in place.

The body of the improved crate comprises sides designated generally at A and the ends designated generally at B. The 45 crate is provided with a top or cover C and a bottom D.

Each side A of the crate is constructed 50 of a vertical series of normally horizontally side members 1 having the general form of slats. The slats or members 1 are preferably approximately square in cross section 55 and are arranged in spaced parallel relation to each other. In a like manner, the ends B

of the crate are formed of slat-like members 2 resembling the members 1 but shorter and arranged in spaced parallel relation to each other. The members 1 and 2 have their adjacent contiguous end portions, overlapped and superimposed one upon the other as shown at 3, resembling the structure of an ordinary log cabin. Such overlapped contiguous end portions of the side portions 1 and 2 are pivotally connected together by hinge pins which are inserted through all of said contiguous end portions of the side and end members 1 and 2, said pins 4 contributing to the folding of the crate from 60 the set up position illustrated in Fig. 1 to the collapsed or folded position shown in Fig. 3.

Each of the end members 2 is formed of substantially twin sections as shown, each 65 of said sections having its inner end scarfed or rabbeted in triangular formation as indicated at 5, such rabbeted ends being overlapped as shown and pivotally connected together by a hinge pin 6. Said hinge pin 80 passing through all of the overlapped twin sections of the end members 2 at the adjacent end of the crate. Interposed between such overlapped and inner ends of the twin sections of the end frame members 2 are combined spacing, stop or limiting blocks 7, 85 each of which is preferably square in cross section, or of the same cross sectional shape as the side and end members 1 and 2. The hinge pins 6 pass through said spacing and stop blocks so that the latter are adapted to turn freely upon said hinge pins during the 90 inward and outward folding movements of the crate. At all times, said spacing blocks hold the end members 2 in proper spaced 95 relation to each other. When the crate is folded to the position shown in Fig. 3, said stop blocks rest between the adjacent side members 1 of the crate and support said side members in relation to each other so as to 100 resist and withstand crushing strains when crates are packed or stored one upon another in piles. This adds greatly to the life and durability of the crate which is ordinarily subjected to the roughest handling upon the 105 return shipment thereof in a folded or collapsed position. Such crushing strains are additionally provided for by the special formation of the scarfed ends of the end members 2 of the crate, the scarfs being so 110 formed as to provide abutting longitudinally elongated and obliquely disposed shoulders 8

which rest in contact with each other when the crate is fully folded.

The bottom D rests upon and is supported when in place by cleats 9 extending longitudinally thereof and fastened to the inner sides of the bottom side members 1 of the crate. Said bottom thus serving to hold the crate in its set up or expanded and receiving or carrying position. The top or 10 cover C is provided on the under side thereof with longitudinally extending cleats 10 which fit between the upper side members 1, thus serving to hold the crate expanded. One of the upper side members 1 of the 15 crate is provided with upstanding eyes 11 which are designed to receive pins 12 extending laterally from said top or cover for the purpose of holding the latter in place. The other side is provided with the staples 11' 20 which with the hasps 12' on the cover coöperate to lock the parts together.

I do not desire to be limited to any special form and arrangement of the top and bottom of the crate and the means for holding 25 said top and bottom in place and detaching them, as it will be apparent that the crate is susceptible of changes in the form, proportion and minor details of construction which may accordingly be resorted to without de- 30 parting from the principle or sacrificing any of the advantages of the invention.

I claim:

1. A folding crate embodying side wall slat like members arranged in spaced parallel 35 relation to each other, and end wall slat like members also arranged in spaced parallel relation to each other, said end wall members and side wall members having their contiguous end portions overlapped and super- 40 imposed one upon another, a hinge pin inserted through such end portions at each corner of the crate, the end wall members each consisting of twin sections having their inner ends scarfed and overlapped, spacing 45 and stop blocks interposed between the end members where they overlap each other, and

hinge pins inserted through such scarfed and overlapped ends of the end members and also through said blocks.

2. A folding crate embodying side wall 50 slat like members arranged in spaced parallel relation to each other, and end wall slat like members also arranged in spaced parallel relation to each other, said end wall members and side wall members having their contiguous end portions overlapped and superimposed one upon another, a hinge pin inserted through such end portions at each corner of the crate, the end wall members each consisting of twin sections having their inner ends scarfed and overlapped, spacing 55 and stop blocks interposed between the end members where they overlap each other, and hinge pins inserted through such scarfed and overlapped ends of the end members and 60 also through said blocks, said blocks serving as means to limit the folding movement of the crate sides toward each other and brace the structure against crushing strains when 65 folded.

3. A folding crate embodying side wall 70 slat like members arranged in spaced parallel relation to each other, and end wall slat like members also arranged in spaced parallel relation to each other, said end wall members 75 and side wall members having their contiguous end portions overlapped and superimposed one upon another, a hinge pin inserted through such end portions at each corner of the crate, the end wall members 80 each consisting of twin sections having their inner ends scarfed and overlapped, spacing and stop blocks interposed between the end members where they overlap each other, and hinge pins inserted through such scarfed and 85 overlapped ends of the end members and also through said blocks, the overlapping ends of said end members being so scarfed as to provide abutting stop shoulders which resist crushing strains when the crate is folded. 90

In testimony whereof I affix my signature.

JOHN D. FINNEGAN.
